UNITED STATES PATENT OFFICE.

GEORGE M. McCLOSKEY, OF NEW YORK, N. Y.

CLOSET CONNECTION.

No. 902,897.

Specification of Letters Patent.

Patented Nov. 3, 1908.

Application filed September 1, 1907. Serial No. 391,630.

To all whom it may concern:

Be it known that I, GEORGE M. McCLOSKEY, a citizen of the United States, and a resident of New York, county of Kings, and 5 State of New York, have invented certain new and useful Improvements in Closet Connections, of which the following is a full, clear, and exact description.

This invention relates more particularly to 10 the soil connections of water closets; and the primary object thereof is to provide simple and efficient means whereby the soil connection may be removably held to the base or flange of the usual closet in such a 15 way as to provide a perfect closet connection having a proper seal; which dispenses with the usual wipe joint, brass floor flange etc.; and which permits the base of the closet to be quickly and readily adjusted and positively held to the connection so that the 20 closet may be readily placed at any desired angle with respect to the connection.

A further object of the invention is to provide a soil connection or fitting for a closet of 25 iron or like metal, which dispenses with the usual lead bend, and which permits not only the vent to be connected thereto, but also provides means whereby one or more waste connections leading from a bath or other 30 fixture may be connected therewith, thereby avoiding the objection which permits only the vent to be connected as in the usual system, and which connection has a part of the sealing head made removable so that the fitting 35 may be more readily cast and handled, and which in case of being broken or injured may be readily removed.

The invention will be hereinafter more particularly described with reference to the accompanying drawings, which form a part of 40 this specification, and will then be pointed out in the claims at the end of the description.

In the drawings, Figure 1 is a vertical section, partly in elevation, of one form of device embodying my invention. Fig. 2 is an enlarged section taken on the line II—II of Fig. 4. Fig. 3 is a detail plan of a swivel or device forming a part of the fastening means. 50 Fig. 4 is an enlarged longitudinal section taken on the line IV—IV of Fig. 5. Fig. 5 is a detail plan, partly broken away, of the fitting or connection; and Fig. 6 shows a slightly different form of closet base.

55 The closet 10 has a discharge 11, and a base 12, and may be of the usual or of any

preferred construction. The base 12 has a projecting flange 13 forming a continuation of the discharge 11, and is provided with an annular recess 14, and a projecting flange 15 60 concentric with the flange 13, and which is somewhat longer than said flange 13. These flanges 13 and 15 provide an annular space 16, which forms a continuation of the recess 14 of the base 12, and fitting this space 16 is 65 a flange 17 of the soil connection 18. This connection 18 may be in the form of an ell and is preferably of iron, and has a horizontal soil pipe or portion 19 and a sealing head 20. This head 20 has its top edge flush with 70 the floor and may be formed integral with the pipe portion 19 or removable therefrom, and said head has a vertical flange 17 which forms a part of the head, and is preferably integral with the portion 19. A flange or 75 member 21 extends upward from the horizontal base 22 of the sealing head 20, and said base 22 is provided with open-ended angular slots 23 projecting inward and in which may be arranged bolts 24 which are 80 adapted to pass through apertures in a horizontal flange 25 on the interior of the removable flange 21, by which the said flange of the sealing head is removably held to the base 22. This flange 21 has a pendent portion 26 85 beneath the flange 25, which is adapted to fit over the outer edge of the base 22 so as to make a neat joint at this point, and the flange 25, as well as the part 26 of the flange 21, is cut away to fit over a slightly projecting portion 27 of the base 22, the said projecting portion 27 serving as a registering means in placing the removable flange 21 in position and to prevent rotary movement of the same on the base 22, so that the bolts 85 may be readily placed in position to hold the flange to the portion 19. By this means the sealing head may be more readily made, and in case of breakage or for other reasons it may be readily replaced without destroying 100 or removing any other part of the fitting.

The flange or member 21 with the member 17 forming the sealing head provide an annular space 28, in which projects the flange 15 extending downward from the closet base. 105 This space 28 forms a sealing chamber, and in said chamber may be a suitable medium 29 such as plaster of paris, paraffin, mercury or other suitable material, and said sealing medium is placed within the chamber 28 110 after the flange 21 of the sealing head has been placed in position.

To permit the closet to be positively held to the connection 18 and to be adjusted at any angle relatively thereto, I provide upon the vertical flange or member 17 of the sealing head 20 an interior horizontal flange 30, which projects within the chamber 28 over the base 22. This flange 30 provides an annular space 31 above the base 22, and in this space is adapted to move the swivel or device 32. This device 32 may be of any desired form whether semi-circular or round, in which latter case it would be made in two parts and held together. As shown it is substantially semi-circular, and for the greater part of its length is L-shaped in cross-section so as to fit in the space 31, and has projecting ends 33 which project above the horizontal flange 25 of the sealing-head flange 21. In each end 33 is a slot 34 which may be enlarged at one part so that the head of a bolt 35 may be passed therethrough, and the body of the bolt forced into the narrower portion to hold the head of the bolt under the ends. These bolts 35 project upward within the sealing chamber 29 through openings in the base 12, and on the upper end of said bolts are nuts 36 or other fastening means, though instead of the key-shaped slots 34 shown, other forms of slots or means may be provided for holding the bolts to the device 32. The closet may thus be set and positively held in any desired position relatively with respect to the fitting or connection.

When the connection 18 is of iron, it may have the openings 37 on each side thereof at or near the bend to which the usual vents may be connected at either side thereof, and it may also have openings 38 at the side thereof to which the waste may be connected from bath-tubs, basins or other means. The fitting or connection 18 is made so that either or both openings 37 and 38 may be used or only one of each, in which case the other may be closed with a suitable plug, thus adapting the fitting to be used either as a right or left-hand connection.

If the sealing medium within the chamber is of a kind that becomes very hard, as plaster of paris for example, and if it is desired to remove the fitting, it often happens that the flange projecting from the closet base will break during such removal, particularly if both flanges of the sealing head are integral with the rest of the fitting. In such case I may make the flange 39 removable as shown in Fig. 6. The flange 39 may be of any suitable material, whether porcelain or metal, and said flange has its upper end fitting an annular recess 40 in the closet base 12, around which may be a suitable sealing medium 41 to prevent the escape of gases around the same. This flange 39 may have lugs through which the screws 43 or other means pass and by which the flange may be held to the closet base. It will be understood that the outer

flange 29 of the sealing head is always removable when a liquid or semi-liquid sealing medium is used, or a medium to which heat may be applied to soften, as paraffin, and that when a sealing medium is used in the head 20 which makes the flange 29 substantially integral with the other part or parts of the connection, the said flange in such a case would not be removable without in some way loosening said medium. However, it will be understood that the flange 29 may be removable at any time when the connection is not attached to a closet, and that the invention is not limited to a removable flange, as in some instances the said flange may be fixed or made to form a permanent part of the connection.

From the foregoing it will be seen that simple and efficient means are provided whereby a perfect seal is secured between the closet and the soil connection; that the closet may be positively held to the connection or fitting and adjusted relatively thereto and sealed in such a way that the closet may be readily removed from the fitting; that the outer member of the sealing head may be quickly and readily removed and another placed in its stead in case of breakage or for other reasons, and that simple means are provided whereby the usual lead bend with its objectionable features are dispensed with, and the waste from bath-tubs, basins, and the like connected direct with the soil pipe.

Having thus described my invention, I claim as new and desire to secure by Letters Patent:—

1. A soil connection provided with two flanges forming an annular chamber, bolts removably holding the outer flange to the connection, a device within the chamber and movable relatively thereto, and bolts adapted to hold the base of a suitable closet to the device so that the latter may be adjusted relatively to the connection.

2. A soil connection for closets, provided with vertical annular flanges forming a sealing chamber, a movable device held within the chamber, and bolts adapted to hold the closet to the device so that the latter may be adjusted to the connection.

3. The combination with a closet base having a pendent flange, of a soil connection having a vertical flange which projects within the pendent flange of the closet base, a vertical removable outer flange forming an annular sealing chamber with the second mentioned flange into which the flange of the closet base projects, a horizontally extending flange on the connection forming a base for the sealing head and connection within the outer removable flange, means projecting inward within the chamber over said base, and bolts for fastening the removable flange to the base.

4. The combination with a closet having a

- pendent flange, of an L-shaped soil connection provided with two vertically-extending annular flanges forming an annular chamber into which the flange of the base projects, 5 bolts for removably holding the outer flange to the connection, a device adjustably held within the chamber, and bolts holding the closet to the device so as to be adjusted relatively to the fitting.
- 10 5. The combination with a closet having a pendent flange, of a soil connection provided with vertical annular flanges forming a chamber into which the said closet flange projects, means for removably holding the outer flange 15 to the connection, an adjustable device held within the chamber, and means for holding the closet to the device so as to be adjusted relatively to the connection.
6. The combination with a closet having a flange projecting downward therefrom, of a soil connection having flanges forming a sealing head providing an annular chamber in which the flange of the closet base projects, 20 an independent device movably held within the chamber, and means connecting the device with the base of the closet and adapted to adjustably hold the closet and connection together.
7. A soil connection having a sealing head 25 providing an annular sealing chamber, an independent device entirely located and adjustably held within the chamber, and means connected with the device adapted to hold the connection to a closet base.
- 30 8. A soil connection having a flange forming a part of a sealing head, a removable member forming the outer portion of the sealing head and removably held to the connection so as to provide an annular sealing 35 chamber, an independent device movably held to the connection entirely within the chamber, and means connected to the device adapted to hold the connection to a closet.
9. A soil connection for closets, comprising 40 an iron L-shaped body portion having vent openings on each side thereof for the escape of gas and openings on each side thereof to which the waste for baths and the like may be connected, a sealing head comprising two 45 flanges projecting upward from the body portion and forming an annular chamber adapted to form a seal with the closet, a flange projecting horizontally outward from the connection and forming a base for the sealing 50
- head, an annular horizontal flange within the outer flange of the sealing head adapted to fit over the base of the connection, bolts for removably holding the outer flange of the sealing head to the base, an annular horizontal flange projecting inward from the inner flange of the sealing head within the sealing chamber, a semi-circular movable device held under the horizontal flange of the inner vertical flange and within the sealing chamber and provided with slotted ends, and bolts 55 adapted to hold the connection to the closet base.
10. A soil connection for closets, comprising a body portion having vents for the escape of gas and an opening on each side thereof to which the waste for baths and the like may be connected, a sealing head having two flanges projecting upward from the body portion and forming an annular chamber adapted to form a seal with the closet, 60 means within the outer flange of the sealing head adapted to fit over the base of the connection, means for removably holding the outer flange of the sealing head to the connection, an annular flange projecting inward from the inner flange of the sealing head within the sealing chamber, a movable device held under the annular flange within the sealing chamber and provided with slotted ends, and bolts 65 adapted to hold the connection to the closet base.
11. A soil connection for closets, comprising a body portion, a sealing head having two flanges projecting upward from the body portion and forming an annular chamber adapted to form a seal with the closet, a flange projecting horizontally outward from the connection and forming a base for the sealing head, an annular flange projecting 70 inward from the inner flange of the sealing head within the sealing chamber, a semi-circular movable device held under the annular flange within the sealing chamber, and means engaging the movable device and 75 adapted to hold the connection to the closet base.
12. A soil connection for closets, comprising a body portion, a sealing head having two flanges projecting upward from the body portion and forming an annular chamber adapted to form a seal with the closet, a flange projecting horizontally outward from the connection and forming a base for the sealing head, an annular flange projecting 80 inward from the inner flange of the sealing head within the sealing chamber, a semi-circular movable device held under the annular flange within the sealing chamber, and means engaging the movable device and 85 adapted to hold the connection to the closet base.
13. A soil connection for closets, comprising a body portion, a sealing head having two flanges projecting upward from the body portion and forming an annular chamber adapted to form a seal with the closet, a flange projecting horizontally outward from the connection and forming a base for the sealing head, an annular flange projecting 90 inward from the inner flange of the sealing head within the sealing chamber, a semi-circular movable device held under the annular flange within the sealing chamber, and means engaging the movable device and 95 adapted to hold the connection to the closet base.
14. A soil connection for closets, comprising a body portion, a sealing head having two flanges projecting upward from the body portion and forming an annular chamber adapted to form a seal with the closet, a flange projecting horizontally outward from the connection and forming a base for the sealing head, an annular flange projecting 100 inward from the inner flange of the sealing head within the sealing chamber, a semi-circular movable device held under the annular flange within the sealing chamber, and means engaging the movable device and adapted to hold the connection to the closet base.
